UNITED STATES PATENT OFFICE.

LOOMIS BURRELL, OF LITTLEFALLS, NEW YORK, ASSIGNOR TO D. H. BURRELL & COMPANY, OF LITTLEFALLS, NEW YORK.

MILKING-MACHINE.

SPECIFICATION forming part of Letters Patent No. 784,780, dated March 14, 1905.

Application filed May 13, 1904. Serial No. 207,744.

To all whom it may concern:

Be it known that I, LOOMIS BURRELL, a citizen of the United States, and a resident of Littlefalls, in the county of Herkimer and State 5 of New York, have invented new and useful Improvements in Milking-Machines, of which the following is a specification.

This invention relates to that class of pneumatic milking-machines which are provided 10 with teat-cups having an inner flexible wall or lining in which the teats are received and to which the suction is applied intermittently or by pulsations.

The main objects of the invention are to 15 render machines of this character more practical and efficient than heretofore by producing sharper and more efficient air-pulsations, by producing pulsations simultaneously inside and outside the flexible linings, by producing a positive and effective movement of 20 the flexible lining inwardly and outwardly or toward and from the teats, by applying external air-pressure to the outside of the lining at the same time that the suction is applied 25 to the interior thereof, thereby producing a squeezing and a sucking action simultaneously, and to provide means for admitting air to the pipes in proximity to the cups for quickly relieving the vacuum therein when the 30 suction is cut off from these pipes.

In the accompanying drawings, consisting of four sheets, Figure 1 is an elevation of a milking-machine embodying this invention and showing one set of teat-cups connected 35 with the pulsator. Fig. 2 is a perspective view of the teat-cup connector. Fig. 3 is a horizontal section of the pulsator in line 3 3, Fig. 1, on an enlarged scale. Fig. 4 is a vertical section in line 4 4, Fig. 3. Fig. 5 is a fragmentary vertical section in line 5 5, Fig. 7. Fig. 6 is a similar section in line 6 6, Fig. 8. Fig. 7 is partly a horizontal section through the pulsator in line 7 7, Fig. 4, and partly a vertical section through the teat-cup connector 40 and one of the teat-cups, showing the parts in the position in which the suction is applied to the interior of the linings. Fig. 8 is a similar view showing the parts in the position in which the suction is cut off from the

interior of the linings. Fig. 9 is a fragmentary sectional view of the connector, showing the air-inlet valve closed. Fig. 10 is a similar view showing this valve open. Fig. 11 is a fragmentary vertical section through the reversing-valve of the pulsator and connecting parts in line 11 11, Fig. 3. Figs. 12 and 13 are vertical sections, on an enlarged scale, showing the reversing-valve in different positions. Fig. 14 is an elevation, partly in section, of the reversing mechanism of the reversing-valve. Fig. 15 is a similar view showing a different position of the reversing mechanism. Fig. 16 is a horizontal section in line 16 16, Fig. 14. Fig. 17 is a horizontal section in line 17 17, Fig. 15. Fig. 18 is 65 a fragmentary elevation of the lower portion of the valve-reversing mechanism, showing the same in a different position.

Like letters of reference refer to like parts in the several figures. 70

A represents the milk pail or receptacle upon which the pulsator B is mounted in any suitable manner.

a represents the flexible main milk-pipe through which the milk flows to the pulsator 75 and thence to the milk-pail.

b represents the flexible main air-pipe, which is also connected with the pulsator and which receives no milk.

C represents the connector or coupling, 80 which is arranged near the teat-cups D and which connects the main milk-pipe a and main air-pipe b with the flexible branch milk-pipes a' and flexible branch air-pipes b', extending from the connector up to the cups. The branch 85 milk-pipes a' are arranged on one side—the milk side—of the connector, to which side the main milk-pipe a is attached, and the branch air-pipes b' are arranged on the opposite side—the air side—of the connector. 90

The main milk-pipe, main air-pipe, connector, branch pipes, and cups are preferably duplicated for each pail and pulsator, so that the latter can be connected with two cows at the same time.

The pulsator is constructed as follows: B' represents the base-plate of the pulsator, which plate rests detachably and tightly, preferably

by means of a rubber packing-ring b^2 , Fig. 4, upon the top of the pail. b^3 is the nipple on this plate, to which the suction-pipe b^4 is applied, which connects the pail with the usual 5 vacuum-pump or exhaust apparatus.

E represents an upright cylinder or valve-casing formed on or secured centrally to the plate B' and containing a piston-valve F, on the under side of which the partial vacuum in 10 the pail acts. A rod g extends upwardly from the valve to a flexible diaphragm G, which forms the bottom of an exhaust-chamber g' , mounted on a casing g'' , which rises from the cylinder E. The casing g'' is provided with 15 openings g^3 or is otherwise so formed that the pressure of the atmosphere acts against the under side of the diaphragm and the upper side of the piston-valve. The partial vacuum in the pail acts constantly on this valve and 20 causes the same to move downwardly except when this downward pressure is overcome by the greater upward pressure which is exerted by the atmosphere against the diaphragm when the same suction is applied to the suction-chamber above the diaphragm, the latter 25 being for that purpose sufficiently larger in area than the piston-valve.

The piston-valve F is provided with a bore or cavity f , which is closed at the top and 30 opens downwardly and into which the milk-ports f' and the air-exhaust ports f'' open, Figs. 4 to 8. These ports are duplicated to connect with the milk-ports f^3 and air-ports f^4 of the cylinder. The milk-ports f^3 of the 35 cylinder communicate with the rigid milk-pipes f^5 , which extend horizontally over the base-plate of the pulsator and carry cocks f^6 at their outer ends, to which the flexible milk-pipes a are connected. In like manner the 40 air-ports f^4 of the cylinder connect with rigid air-pipes f^7 , which are connected by cocks f^8 with the flexible air-pipes b .

The milk-ports f^3 and air-ports f^4 of the cylinder or valve-casing are arranged in the 45 same horizontal plane, while the milk-ports f' of the valve are arranged at a higher level than that of the air-exhaust ports f'' thereof, so that in the lower position of the valve (shown in Figs. 5 and 7) the milk-ports of the valve 50 register with the milk-ports of the cylinder and the main milk-pipes, while the air-exhaust ports of the valve are out of register. In the raised position of the valve (shown in Figs. 6 and 8) the air-exhaust ports of the valve are 55 in register with the air-ports of the cylinder and with the main air-pipes and connect these air-pipes with the exhausted interior of the milk-pail.

The piston-valve F is further provided with 60 an air relief or inlet port f^9 , which enters from the top and opens at the side at the level of the milk-ports f' of the valve. This relief-port divides into two branches, as shown in Fig. 7, which register with the air-ports f^4 of the cylinder when the valve is in its lower

position and the milk-ports of the valve register with the milk-pipes. When the valve is in its raised position, Fig. 6, this relief-port is closed at its lower end. When the valve is in its lower position, Figs. 5 and 7, this relief-port is in register with the air-ports f^4 of the cylinder and admits outside air to the air-pipes. 70

Each milk-pipe f^5 is preferably formed by a glass tube, which is fitted at its inner end 75 against a rubber washer f^{10} in a boss f^{11} on the valve-cylinder and at its outer end against a rubber washer f^{12} in a boss f^{13} , which is formed on the base-plate of the pulsator and into which the cock f^6 is screwed. This transparent pipe enables the operator to observe the flow of the milk, and as the pipes are straight they can be readily cleaned. 80

The exhaust-chamber g' above the diaphragm G is alternately placed in communication with the exhausted interior of the pail or with the external air by means of a valve H, which is preferably constructed and arranged 85 as follows:

The valve is arranged flatwise upon the 90 base-plate of the pulsator above a port h , which penetrates the base-plate and opens into the pail, and a port h' , which also penetrates the plate, but is connected on the under side of the plate with a horizontal pipe or passage 95 h^2 , Figs. 11-13, which communicates with the exhaust-chamber g' by an ascending pipe h^3 and passage h^4 , Figs. 3 and 4. The ascending pipe is preferably provided with a hand-screw h^5 or some other suitable device for 100 regulating the size of the opening.

The valve is provided in its under side with an exhaust-cavity h^6 , by which the ports h h' can be placed in communication, as shown in Fig. 13, in which position of the valve the 105 exhaust applied to the pail is also applied to the exhaust-chamber g' , thereby causing the diaphragm G to be drawn upwardly and the piston-valve F to be raised. The valve is further provided with an air-port h^7 , which penetrates the valve and which when in register with the port h' of the plate, as shown in Fig. 12, admits the external air to this port and through the same and the connecting-passages to the diaphragm g' , thereby allowing the 115 diaphragm to descend under the suction applied to the piston-valve.

The reversing-valve H is mounted to oscillate on a vertical pivot h^8 , Figs. 3, 7, and 8, 14 and 15, and its movement is limited by 120 arms h^9 on the valve and an intermediate stop h^{10} on the base-plate. This reversing-valve is shifted periodically by mechanism from the piston-valve F. While the piston-valve is moving downwardly the air-port of the reversing-valve is in register with the port h' and admits the external air to the diaphragm-chamber g' , Figs. 3 and 7. When the piston-valve has reached the limit of its downward movement, the reversing-valve is reversed 130

from the position shown in Figs. 3 and 7 to the position shown in Fig. 8. In this position the air-port of the reversing-valve is closed and the exhaust is connected with the 5 diaphragm-chamber through the exhaust-cavity of the reversing-valve. The piston-valve is now moved upwardly by the diaphragm until the limit of the upward movement is reached, when the reversing-valve is again 10 reversed.

The mechanism by which the up-and-down movement of the piston-valve is transmitted to the reversing-valve for reversing the same preferably contains a spring which is gradually strained or deflected by the movement of 15 the piston-valve and which is released by an escape mechanism to become active when the movement of the piston-valve has nearly reached the desired limit and then acts with 20 full force upon the reversing-valve for shifting the same, so that the force created by the slow movement of the piston-valve is stored up in the spring and then applied suddenly to the valve, whereby the shifting of the reversing-valve is effected quickly and with certainty notwithstanding the slow movement of the piston-valve. This valve-shifting mechanism is 25 preferably constructed as follows, Figs. 3, 7, 8, 14 to 18: I is a horizontal arm which is 30 secured to the rod g of the piston-valve in the casing g^2 , and i is a bar which extends downwardly from the arm I on the outer side of the valve-cylinder E and connects at its lower end by a pin i^2 and slot i^3 or other suitable 35 means with one end of a vertically-oscillating reversing-lever I'. The latter is pivoted at i^3 to a standard i^4 , which is secured to the base-plate of the pulsator. I² is a valve-lever which is pivoted intermediate its ends 40 to the standard i^4 and which is operated from the reversing-lever I' by a bar-spring i^5 . This spring is secured at its lower end to the reversing-lever by a bracket i^6 or other suitable means and is slidably connected with the 45 upper arm i^7 of the valve-lever I², preferably by engaging between two lugs i^8 on the lever. The locking or free end of the reversing-lever is arranged adjacent to the lower arm i^9 of the valve-lever and is provided on its front 50 side with a locking-lug i^{10} , which engages in the normal position of the reversing-lever against one or the other side of a stop-pin i^{11} on the valve-lever. When the bar i is moved downwardly by the piston-valve, the opposite 55 or locking arm of the reversing-lever moves upwardly. In this position of the parts the locking-lug i^{10} on the locking-arm of the reversing-lever bears against the outer side of the pin i^{11} on the valve-lever, as shown in 60 Fig. 15, and prevents movement of the valve-lever until the locking-arm has moved upwardly far enough to cause the locking-lug to clear the locking-pin. During this movement of the reversing-lever the spring is bent 65 and strained and when the locking-lug has

finally cleared the locking-pin the tension of the spring quickly shifts the valve-lever and reverses the valve, as shown in Fig. 14. The bar i is now moved upwardly, and the downward movement of the locking-arm of the reversing-lever places the lug on the inner side of the pin and prevents the valve-lever from moving under the pressure of the spring until the lug has passed below the pin. The spring has now been strained and when the 70 valve-lever is released by the lug on the reversing-lever passing below the pin on the valve-lever the latter is shifted by the tension of the spring and the valve is again reversed. The lower end of the valve-lever engages between arms or jaws i^{12} on the valve, as represented in Figs. 3, 7, and 16. This mechanism for shifting the valve is very satisfactory and is preferred; but other means for effecting 75 this result may be employed.

The teat-cups D, as stated, are of the kind in which an inner flexible lining d is combined with a rigid inclosing shell d' . The suction is applied alternately to the inner compartment formed within the flexible lining and 80 the outer compartment formed between the flexible lining and the rigid shell. A flexible mouthpiece d^2 of well-known construction is arranged in the top of each cup to make a close connection with the teat. The bottom 85 of each cup is provided with a nipple d^3 for connection with the branch milk-pipe a' , and the upper portion of each cup is provided at the side with an oblique nipple d^4 for connection with the branch air-pipe b' . As shown 90 in the drawings, the rigid shell of the cup is composed of an upper and a lower part connected by a screw-coupling d^5 ; but other constructions may be employed.

The connector C is not only a manifold coupling for connecting the four branch milk-pipes and four branch air-pipes with the main milk-pipe and the main air-pipe, respectively, but also a device for admitting the external air automatically to the branch milk-pipes for 105 relieving the partial vacuum therein when the suction is cut off from the main milk-pipe by the piston-valve. This connector is constructed as follows, Figs. 1, 2, 7 to 10: The connector consists of a tubular milk-passage k , a 110 tubular air-passage l , and an intermediate valve-chamber m . The milk-passage k is connected at its open outer end with the main milk-pipe a and is provided with four nipples k' , to which the branch milk-pipes are connected. The air-passage l is curved at its outer 115 end and similarly connected at its outer end with the main air-pipe b and is provided with four nipples, to which the branch air-pipes b' are connected. As hereinbefore stated, 120 the branch milk-pipes connect with the nipples at the lower ends of the teat-cups and communicate with the internal compartment or space formed within the flexible lining, while the branch air-pipes connect with the 125 130

external nipples at the upper portion of the cups and communicate with the external compartments or spaces formed between the linings and the outer shells of the cups.

- 5 The valve-chamber m contains an air-inlet valve m' , which divides the chamber into two parts, one communicating with the milk-passage k and the other with the air-passage l . This valve is preferably a flexible diaphragm, 10 which seats itself against a seat m^2 , arranged around an opening m^3 , leading to the milk-passage. The valve-chamber is provided on the same side with an air-inlet orifice m^4 , through which the external air enters the 15 valve-chamber and passes to the milk-passage when the valve is raised from its seat. The valve is held yieldingly against its seat by a spring n , which is, however, not so strong that it cannot be overcome by the air-pressure 20 when the suction is applied to the air-passage l . The valve-diaphragm is preferably provided on its back with a plate n' and stem n^2 , to which the spring is applied. The valve-chamber is preferably formed of two parts, 25 between which the diaphragm is clamped and which are secured together by screws O or other fastenings.

When the suction is applied to the milk-pipes and through the same to the interior of 30 the cup-linings and the air is admitted to the air-pipes, the valve m' closes and prevents the entrance of air to the milk-pipes. When the suction is applied to the air-pipes and through the same to the exterior of the cup-linings, the 35 valve m' opens and admits air to the milk-pipes and the interior of the cup-linings. The valve is in this manner opened and closed automatically by the pulsations in the air-pipe.

The pulsator is preferably provided with 40 the usual handle P , having its uprights p secured at their lower ends to the base-plate and curled at their upper ends to form supports p' for the flexible pipes in carrying the pulsator from place to place.

- 45 The operation of the apparatus is as follows: Suction being applied to the milk pail or vessel, the piston-valve moves slowly up and down in its cylinder and produces pulsations in the milk and air tubes connected therewith. 50 These pulsations take place in such manner that when the suction is applied to the milk-pipes and through the same to the internal compartments or internal spaces of the flexible linings of the teat-cups the external air is 55 admitted to the air-pipes and through the same to the external compartments of the teat-cups outside of the linings, thereby applying the suction to the teats within the linings and at the same time applying external air-pressure 60 to the outer sides of the linings. In this manner the teats are squeezed at the same time that the suction is applied to the same. When the suction is cut off from the milk-pipes and the internal space of the cup-linings, the suction 65 is applied to the air-pipes and the outer

sides of the cup-linings, whereby the linings are drawn away from the teats against the shells of the cups, and the teats are allowed to hang nearly free in the cups. The vacuum in the linings is relieved quickly when the suction is cut off by the air entering the milk-pipes through the connector. In this manner pulsations are produced simultaneously inside and outside of the cup-linings, the operation alternating in such manner that when 70 the suction is applied to the interior of the lining to draw the milk from the teats the external air is admitted to the exterior of the lining to squeeze the teats, and when the suction is applied to the exterior of the linings to 75 draw the latter away from the teats the external air is admitted to the interior of the linings to break the vacuum therein and quickly relieve the teats from the suction. The linings are in this manner positively 80 moved both inwardly and outwardly, and sharp and effective pulsations are produced. When the suction has been relieved on the milk-pipes and the lining has been drawn away from the teat, the cup nevertheless stays on 85 the teat, partly because a slight vacuum remains in the interior space of the lining and partly because the flexible mouthpiece of the cup holds the latter on the teat after the cup has once been drawn up to place thereon. 90

The pulsations are transmitted to the connector and cups as follows: During the time that the milk-ports f' of the piston-valve register with the milk-ports f^3 of the cylinder, which occurs while the piston-valve 100 travels toward its lower position and is in this position, the suction in the pail is applied through these ports to the fixed milk-pipe f^5 , main milk-pipe a , milk-passage k of the connector, and branch milk-pipes a' , as indicated 105 in Fig. 7, and the milk flows through these pipes, passages, and ports to the pail. At the same time the external air is admitted to the exterior of the linings through the air-relief port f^9 in the piston-valve, the cylinder air-port f^4 , the fixed air-pipe f^7 , main air-pipe b , air-passage l of the connector, and branch air-pipes b' , as indicated in the same figure. 110

During the time that the suction is cut off from the milk-pipes by the piston-valve 115 and the air-suction port f^2 of the latter is in communication with the air-pipes, as indicated in Fig. 9, which occurs while the piston-valve travels toward its uppermost position and is in said position, the suction in the pail 120 is applied through the air-exhaust port f^2 , cylinder-port f^4 , fixed air-pipe f^7 , main air-pipe b , air-passage l of the connector, and branch air-pipes b' to the exterior of the cup-linings. At the same time the external air 125 is admitted to the milk-passage k of the connector and the milk-pipes connected therewith by the valve of the connector.

By admitting the air for the relief of the vacuum in the branch milk-pipes near the

cups the vacuum is quickly relieved in the teat-space of the cups; the surging of the milk in the main milk-pipes, which are of considerable length, is avoided, and the construction is improved because pipes of comparatively small size can be used.

The reciprocating movement of the piston-valve is preferably effected, as shown and described, by a reversing-valve and an exhaust-chamber and diaphragm in connection with the suction applied to the pail; but other devices or mechanisms may be applied for the purpose.

I claim as my invention—

15 1. The combination of a teat-cup having a movable inner wall, an air-chamber outside said wall and a milk-chamber inside said wall, and means for producing alternating vacuum pulsations in both of said chambers, substantially as set forth.

20 2. The combination of a teat-cup having a movable inner wall, an air-chamber outside said wall and a milk-chamber inside said wall, means for producing alternating vacuum pulsations in both of said chambers, and means for alternately admitting air to said chambers, substantially as set forth.

25 3. The combination of a teat-cup having a movable inner wall, an air-chamber outside said wall and a milk-chamber inside said wall, means for producing vacuum pulsations in said air-chamber, and an automatic air-inlet valve which is opened by suction applied to the air-chamber and admits air to the milk-chamber, substantially as set forth.

30 4. The combination of a teat-cup having a movable inner wall, an air-chamber outside said wall and a milk-chamber inside said wall, means for producing alternating vacuum pulsations in both of said chambers, and an automatic air-inlet valve which is opened by suction applied to the air-chamber and admits air to the milk-chamber, substantially as set forth.

35 45 5. The combination of a teat-cup having a movable inner wall and an air-chamber outside said wall, an air-passage connected with said outer chamber, a milk-passage connected with the chamber within said movable wall, an exhausting means, and a pulsator which places the exhausting means alternately in communication with said inner and outer chambers, thereby producing alternating vacuum pulsations in both chambers, substantially as set forth.

60 6. The combination of a teat-cup having a movable inner wall and an air-chamber outside said wall, an air-passage connected with said outer chamber, a milk-passage connected with the chamber within said movable wall, an exhausting means, and a pulsator which places the exhausting means alternately in communication with said inner and outer chambers, thereby producing alternating vacuum pulsations in both chambers, and

which is provided with an air-inlet which admits air to the air-passage and outer chamber when it applies the exhaust to the milk-passage and inner chamber, substantially as set forth.

70 7. The combination of a teat-cup having a movable inner wall and an air-chamber outside said wall, an air-passage connected with said outer chamber, a milk-passage connected with the chamber within said movable wall, an exhausting means, a pulsator which places the exhausting means alternately in communication with said inner and outer chambers, thereby producing alternating vacuum pulsations in both chambers, and which is provided with an air-inlet which admits air to the air-passage and outer chamber when it applies the exhaust to the milk-passage, and air-inlet means separate from said pulsator for admitting air to the milk-passage when the exhaust is cut off from the same by the pulsator, substantially as set forth.

75 8. The combination of a teat-cup having a movable inner wall and an air-chamber outside said wall, an air-passage connected with said outer chamber, a milk-passage connected with the interior of said inner wall, and a pulsator-valve connected with said air and milk passages and having a milk-port, an air-exhaust port and an air-inlet port, said ports being so arranged that either said milk-port and said air-inlet port are in register with said milk-passage and said air-passage, respectively, or said air-exhaust port is in register with said air-passage and said milk-port is closed, substantially as set forth.

90 9. The combination of a teat-cup having a movable inner wall and an air-chamber outside of said wall, an air-passage connected with said outer chamber, a milk-passage connected with the interior of said movable wall, a pulsator which admits air to said air-passage and simultaneously applies suction to said milk-passage and which alternately applies suction to said air-passage and cuts off the suction from said milk-passage and the interior of said movable wall, and means for admitting air to said milk-passage when the suction is cut off from the same, substantially as set forth.

95 10. The combination of a teat-cup having a movable inner wall and an air-chamber outside said wall, an air-passage connected with said outer chamber, a milk-passage connected with the chamber within said movable wall, an exhausting means, and a pulsator having a valve-casing which is connected with said exhausting means and provided with a milk-port and an air-port, and a reciprocating valve arranged in said casing and provided with a milk-port, an air-exhaust port and an air-inlet port, said air-exhaust port and air-inlet port being adapted to register alternately with the air-port of the valve-casing, substantially as set forth.

11. The combination of a milk-receptacle, means for exhausting the same, a pulsator having an upright valve-cylinder which opens at its lower end into said receptacle, a pulsator-valve arranged to move up and down in said cylinder and exposed to the suction in the receptacle, whereby the valve is caused to move downwardly, and means for moving the valve upwardly, substantially as set forth. 70
12. The combination of a milk-receptacle, means for exhausting the same, a pulsator having an upright valve-cylinder which opens at its lower end into said receptacle, and a pulsator-valve arranged to move up and down in said cylinder and exposed to the suction in the receptacle, whereby the valve is caused to move downwardly, said valve being provided with a milk-port, an air-exhaust port, and an air-inlet port, substantially as set forth. 75
13. The combination of a milk-receptacle, means for exhausting the same, a pulsator having an upright valve-cylinder which is open at its upper end to the atmosphere and communicates at its lower end with the milk-receptacle, said cylinder having a milk-port and an air-port in its side, and a pulsator-valve in said cylinder having a milk-port adapted to register with the milk-port of the cylinder and opening through the lower end of the valve, 80
- an air-exhaust port adapted to register with the air-port of the cylinder and opening through the lower end of the valve, and an air-inlet port adapted to register with the air-port of the cylinder and opening to the atmosphere through the upper end of the valve, substantially as set forth. 85
14. The combination of a teat-cup, an exhausting means, and a pulsator having a valve-casing open at one end to the atmosphere and 90 at the other end to the exhausting means, a reciprocating pulsator-valve arranged in said casing, an exhaust-chamber provided with a movable member which is connected with said valve for moving the same in one direction, 95
- and means for alternately connecting said exhaust-chamber with the exhausting means or with the atmosphere, substantially as set forth. 100
15. The combination of a milk-receptacle, means for exhausting the same, a pulsator having a valve-casing which is open at one end to the atmosphere and at the other end to the receptacle, a reciprocating pulsator-valve arranged in said casing, an exhaust-chamber provided with a movable member which is connected with said valve for moving the same in one direction, and means for alternately connecting said exhaust-chamber with said milk-receptacle or with the atmosphere, substantially as set forth. 110
16. The combination of a milk-receptacle, means for exhausting the same, a pulsator having a valve-casing which is open at its lower end to the receptacle and at its upper end to the atmosphere, a piston-valve adapted 115
- to move up and down in said casing and exposed to the suction in said receptacle, an exhaust-chamber arranged above said valve and provided with a movable member which is connected with said valve for raising the same, 70
- and means for alternately applying suction or admitting air to said exhaust-chamber, substantially as set forth. 120
17. The combination of a milk-receptacle, means for exhausting the same, a pulsator having a valve-casing which is open at its lower end to the receptacle and at its upper end to the atmosphere, a piston-valve adapted to move up and down in said casing and exposed to the suction in said receptacle, an exhaust-chamber arranged above said valve and provided with a movable member which is connected with said valve for raising the same, 80
- and a reversing-valve by which said exhaust-chamber is alternately connected with said receptacle or with the atmosphere, substantially as set forth. 85
18. The combination of a teat-cup, an exhausting means, and a pulsator having a valve-casing open at one end to the exhausting means and at the other to the atmosphere, a piston-valve adapted to reciprocate in said casing and exposed to the suction created by the exhausting means, an exhaust-chamber provided with a movable member which is connected with the valve for moving the same in one direction, a reversing-valve by which the exhaust-chamber is alternately connected with the exhausting means or with the atmosphere, and a spring reversing mechanism 100 which is operated by said reciprocating pulsator-valve and which shifts said reversing-valve at the end of the stroke of said pulsator-valve, substantially as set forth. 105
19. The combination of a milk-receptacle, means for exhausting the same, a pulsator having a valve-casing which is open at its lower end to the receptacle and at its upper end to the atmosphere, a piston-valve adapted to move up and down in said casing and exposed to the suction in said receptacle, an exhaust-chamber arranged above said valve and provided with a movable member which is connected with said valve for raising the same, a reversing-valve by which said exhaust-chamber is alternately connected with said receptacle or with the atmosphere, and a spring reversing mechanism which is operated by said reciprocating pulsator-valve and which shifts said reversing-valve at the end of the stroke of said pulsator-valve, substantially as set forth. 110
20. The combination of a milk-receptacle, means for exhausting the same, a pulsator having a valve-casing which is open at one end to the atmosphere and at the other end to the receptacle, a reciprocating pulsator-valve arranged in said casing, an exhaust-chamber provided with a movable member which is connected with said valve for moving the same 115

in one direction, a conduit leading to said exhaust-chamber, and a reversing-valve which has an air-port and an exhaust-cavity and which alternately places said passage in communication with said receptacle or with the atmosphere, substantially as set forth.

21. The combination of a milk-receptacle, means for exhausting the same, a pulsator having a valve-casing which is open at one end to the atmosphere and at the other end to the receptacle, a reciprocating pulsator-valve arranged in said casing, an exhaust-chamber having a movable member which is connected with said valve, an exhaust-port leading to the milk-receptacle and a passage leading to the exhaust-chamber, said port and passage being arranged in the base-plate of the pulsator, a reversing-valve arranged on said base-plate over said port and passage and provided with an air-port and an exhaust-cavity, and means for shifting said reversing-valve from said pulsator-valve, substantially as set forth.

22. The combination of a milk-receptacle, means for exhausting the same, a pulsator having a base-plate applied to the same and provided with a valve-casing, a pulsator-valve arranged therein, an exhaust-chamber provided with a movable member which is connected with said valve, an oscillating reversing-valve arranged on said base-plate and controlling the admission of the exhaust and the external air to said exhaust-chamber, and means for oscillating said reversing-valve from said pulsator-valve, substantially as set forth.

23. The combination of a teat-cup, an exhausting means, and a pulsator comprising a valve-casing open at one end to the exhausting means and at the other to the atmosphere, a piston-valve adapted to reciprocate in said casing and exposed to the suction created by the exhausting means, an exhaust-chamber provided with means for moving said piston-valve, a reversing-valve by which the exhaust-chamber is alternately connected with the exhausting means or with the atmosphere, and connecting reversing mechanism composed of a reversing-lever which is oscillated from the reciprocating valve, a valve-lever connected with the reversing-valve, a spring-bar having opposite ends connected with said levers, and escapement-stops on said levers, substantially as set forth.

24. The combination of teat-cups, a main milk-pipe, a connector interposed between the main milk-pipe and teat-cups, an automatic air-inlet valve in said connector adapted to admit air to said milk-pipe and teat-cups, an air-pipe connected with said connector, and means for producing pulsations in said air-pipe, which pulsations control said air-inlet valve, substantially as set forth.

25. The combination of teat-cups provided

with branch air and milk pipes, a pulsator, a connector to which said branch pipes are connected, main air and milk pipes connected with said connector, and an air-inlet valve in said connector whereby air is admitted to the milk-pipes and which is controlled by the pulsations in the main air-pipe, substantially as set forth.

26. The combination of teat-cups, a main milk-pipe connected therewith, a connector interposed between the main milk-pipe and the teat-cups, an automatic air-inlet valve in said connector which seats itself toward the milk-pipe, an air-pipe which opens against the back of the valve, and means for producing pulsations in said air-pipe, substantially as set forth.

27. The combination of teat-cups, branch milk-pipes and air-pipes connected therewith, a main air-pipe and a main milk-pipe, a connector interposed between said main pipes and branch pipes and comprising two passages, one connecting with the milk-pipes and the other with the air-pipes, and a valve-chamber and automatic air-inlet valve arranged between said two passages, substantially as set forth.

28. A teat-cup connector comprising a valve-chamber, an air-inlet valve arranged therein, a milk-passage arranged on one side of said chamber and provided with a seat against which said valve closes, an air-inlet which is in communication with the milk-passage when the valve is open, and an air-passage which opens on the rear side of said valve, substantially as set forth.

29. A teat-cup connector comprising a valve-chamber, a diaphragm-valve arranged therein, a milk-passage arranged on one side of the valve and provided with a seat against which said valve closes, an air-inlet arranged in the chamber on the same side of the diaphragm-valve, milk-pipe connections provided on said milk-passage, an air-passage opening into said valve-chamber on the opposite side or back of the diaphragm-valve, and air-pipe connections provided on said air-passage, substantially as set forth.

30. The combination of teat-cups, each having an outer air-chamber and an inner milk-chamber, a milk-pipe and an air-pipe, means for exhausting said pipes, a connector interposed between said pipes and said teat-cups, and an automatic air-inlet valve in said connector which seats itself toward the milk-pipe and is opened by suction applied to the air-pipe, substantially as set forth.

Witness my hand this 7th day of May, 1904.

LOOMIS BURRELL.
